UNITED STATES PATENT OFFICE.

REUBEN STANLEY SMITH, OF MILWAUKEE, WISCONSIN, ASSIGNOR, BY MESNE ASSIGNMENTS, TO FIRST WISCONSIN TRUST COMPANY, TRUSTEE, A CORPORATION OF NEW YORK.

FLEXIBLE DIES FOR BENDING THIN METAL PLATES IN THE DIRECTION OF THEIR WIDTH.

Application filed September 12, 1921. Serial No. 500,019.

To all whom it may concern:

Be it known that I, REUBEN STANLEY SMITH, a citizen of the United States, and a resident of the city of Milwaukee, county of Milwaukee, and State of Wisconsin, have invented a certain new and useful Improvement in Flexible Dies for Bending Thin Metal Plates in the Direction of Their Width; and I do declare the following to be a clear, exact, and complete description of the invention, such as will enable persons skilled in the art to which it relates to make and use the same, reference being had to the accompanying drawing for an exposition of the details of one constructional form in which I have chosen to embody my said invention.

In Patent No. 1,466,104 granted August 28, 1923, on an application, Serial No. 367,799, filed on March 22, 1920, by Henry Miller, Frederick Orton and me, as joint inventors, there is disclosed a press for offsetting, or bending edgewise, thin rectangular metal plates, so as to distort the side lines thereof and increase the superficial area of the plate to such an extent that a curved blank, much wider in its extended proportions than the rectangular plate, can be punched therefrom, without the unavoidable and expensive waste of material attending the practice of methods heretofore in vogue.

The press disclosed in the application just referred to, is provided with a bed and a drawing head, which latter reciprocates in a path extending transversely of the bed. Both the bed and the head of the press are equipped with specially designed, contoured, complementary dies, which act respectively upon the opposite edges of the blank, the pressure exerted by the fixed dies carried by the reciprocating head and acting upon one edge of the blank being resisted by the pressure exerted against the other edge of the blank by the relatively stationary dies fixed in the bed of the press. As a result of the pressures thus opposed, in the approach of the dies toward each other, the blank of rectangular form is converted into one of curved or irregular form, and the outlines of which are made to conform closely to the pre-arranged curved lines of the complementary sets of dies carried by the press.

In order that the wide plate may not buckle when pressure is applied to the edges thereof, as described, it is necessary to exert a confining pressure upon the sides of the plate, so that the flow, or displacement of the metal, may occur only in the directions desired. This result is attained by means of mechanism disclosed in the application hereinbefore referred to.

Serious problems are involved in the production of dies suitable for use in plate bending presses of the type referred to, and their manufacture is attended with difficulties. Dies in lengthy sections, and integral die members, are difficult to temper properly without warping, and are subject to fracture by reason of the inability to apply the pressures exerted in the operation of the press upon all parts of the die at the same instant. A broken die of this character involves considerable loss, with a corresponding expense in effecting its replacement. Again, separate dies in lengthy sections, and integral die members, are required to be made for work in which the outlines differ from one another, with a consequent added cost for the production and maintenance of the several different forms or kinds of dies.

The very serious objections adverted to as inhering in the former system of die production, are eliminated by my invention, in which I provide a system of interchangeable dies constructed as units, which may be multiplied as required by the design of any particular work which it may be desired to produce. My invention provides a system of dies in which there exists the greatest degree of flexibility, thereby permitting the die units to be assembled and arranged in the press in accordance with the work which it may be desired to produce. The die units being of small dimensions, are easily secured in position in the press, and may be removed or changed with equal facility. Their separate production is most economically effected.

The die units manufactured in accordance with my invention may be provided with straight, angular or curved acting faces, designed in a complete set to meet the demands of a wide range of work. With a stock of such dies, it is comparatively a simple matter to equip the bending press

with complemental sets of dies, selected with a view to the production of work of desired contour.

Patent No. 1,340,138, granted to Henry Miller, on May 11, 1920, and Patent No. 1,452,255, granted to me on April 17, 1923, disclose the idea of thickening the plate in certain areas, so as to provide an integral reinforcement, to resist breaking strains in the narrower portions of the automobile side bar or other article produced from the blank, after the latter has been cut from the plate. In practice, the reinforcement described is produced by the edgewise compression of the plate in certain sections with a resultant thickening of the same in the areas of compression. To permit the cross flow of the metal in effecting the compression, the die units used in the press to attain the desired result will be provided with a slight clearance to permit the necessary expansion or increase in the gage of the metal.

The features residing in the invention will now be described in detail, and the novelty thereof will be pointed out in the appended claims.

In the drawing which accompanies this specification,

Figure 1 is a plan view of a set comprising upper and lower die members constructed in accordance with my invention, the upper die member being broken away for a portion of its length so as to show the contour of the die units of the lower die member, and a rectangular metal strip as in position between the die members to have an edgewise bending pressure applied thereto.

Fig. 2 is a similar plan view showing the die members as having completed their approach to each other, and the rectangular strip converted into one of curved or irregular form, with the ends thereof somewhat narrowed by the compression exerted in the bending operation.

Fig. 3 is an end view looking from the left of Fig. 1.

Fig. 4 is a view looking from the left of Fig. 2, and showing how the metallic strip is reinforced by an increase in thickness due to compression.

Fig. 5 is a cross-sectional view, it may be at any point in the length of the dies where compression and expansion do not occur, but in the present instance, on the line 5-5, Fig. 2, looking in the direction of the arrow.

Fig. 6 is a diagrammatic plan view, similar to Fig. 1, but showing the action of the dies in imparting an edgewise bend to the metallic strip without curving the same.

Fig. 7 is a view looking from the left of Fig. 6.

In the drawing, the numeral 10 indicates the upper and the numeral 11 the lower of

a pair of bending die members constituting a complemental set, designed for use in the presses hereinbefore referred to. Each member of the set is composed of a plurality of interchangeable units 12, which are adapted to be assembled and secured in proper positions in the movable head and fixed bed, respectively, of the press, so that the acting faces of the units comprising the complemental set of dies will oppose each other. The die units are rectangular plates of hardened steel, and are cut away for a portion of their length to form a transversely extending shoulder 13, which latter constitutes the acting face of the die which bears against the edge of the rectangular plate 14, when the bending pressure is applied to the latter.

The acting faces 13 of the die units may be formed on any lines desired,—either curved, angular or straight,—as may be necessary to produce the predetermined contour in the side or edge lines of the plate, and will be assembled and secured in the press so as to effect the attainment of that purpose. The depth of the face 13 extending from the upper plane surface 15 to the lower plane surface 16 of the die unit, will be determined by the gage of the metal plate which is to be bent. The said lower plane surfaces 16, of the complemental die members, are designed to act with a confining pressure upon the sides of the plate 14, when bending pressure is applied to the edges thereof, so as to resist the tendency of the thin metal plate to buckle in the movement of the dies over each other, and thus preserve the planiform condition of the metal plate throughout its area.

Relative movement of the die members with respect to each other, as described, will convert the rectangular plate 14 shown in Fig. 1, into the curved plate 17 shown in Fig. 2. The comparative increase thus produced in the width of the plate, will enable a curved blank having a corresponding extreme width to be cut or blanked therefrom, with but a relatively small proportion of waste, and effect a saving of approximately 50% in the material used over the present practice of punching a curved blank from a rectangular plate having a width sufficient to accommodate the extreme width of the curved blank.

The plate 14 will be positioned upon the lower plane surface 16 and against the acting face 13 of the lower die member, which is held immovably in the fixed bed of the press. The upper side and other edge of the plate 14, are engaged in a corresponding manner by the upper die member, which rests upon and against the plate 14. The upper plane surface 15 of each die member has a sliding engagement with the lower plane surface 16 of the opposite die member, beyond the edges of the metal plate, in the

movement of the dies under the bending pressure.

The curved blank 17 is intended to be drawn into a channel to form the side bar of an automobile frame, such side bar in its position of use, having a vertical web and flanges extending laterally from the upper and lower edges thereof, as usual. In such a construction, the side bar tapers at its ends, to accommodate the attachment of adjunctive parts of the automobile, and the reduction in the width of the web at these ends has a tendency to weaken the side bar at the points mentioned.

To impart the necessary degree of rigidity to the side bar, and avoid the necessity for the employment of reinforcing attachments of any kind, I propose, in some instances, to form upon the narrower portions of the side bar an integral reinforcement, which is produced by increasing the gage of the metal in the narrower parts of the blank from which the side bar is drawn. This result, as hereinbefore stated, is achieved by thickening the metal in the desired areas by compression exerted against the edges of the plate at the time that the bending pressure is applied. In order to produce this condition, I deepen the acting face 13 in certain of the opposed die units, so as to allow a slight clearance into which the metal of the plate may expand according to the excess pressure applied to the edges thereof. Such excess pressure will cause the metal to flow laterally with relation to the width of the plate and into the clearance spaces provided in the die units, and thus produce an integral reinforcement of the plate in the areas desired.

The manner in which the result described is attained, will be apparent from an inspection of Figs. 3 and 4, and comparison with Fig. 5. The first named views show the deepened acting forces 18 of the die units, while that last mentioned shows the acting faces 13 of the die units as of normal depth and not designed to exert compression. The thickened plate is indicated at 19, in Fig. 4. It will be understood that the die units which are designed to exert compression to effect the thickening of the plate in the desired areas, are caused to approach each other more closely than do the die units whose function is limited to the exertion of bending pressure against the edge of the plate. Such approach is effected by advancing the relative position of the acting faces 18 of the compression die units, so that such faces in the complemental set have less than the normal separation. The integral reinforcement of certain areas of the plate may be produced by deepening the acting face of the complemental die numbers, and where reinforcement only of certain areas of the plate is desired without bending, the die

units in the complemental set will have their acting faces so formed and arranged in the press as to effect this result.

In some classes of work, it is necessary only to effect a simple edgewise bending of the plate, without curving, to adapt it to its intended purposes. Such a bend may be produced by arranging selected die units in the press at separate points with relation to the opposite sides of the plate, in the manner indicated in Fig. 6, wherein die units 20, carried by the transversely moving head of the press, are opposed by a die unit 21, mounted upon the fixed bed of the press, the respective units being staggered or alternated as shown.

With a complete equipment of properly shaped die units, selection may be made therefrom to adapt the press to the production of blanks of any desired outline, inasmuch as such an equipment will cover a large range of variety in the work. Once acquired, such a stock of die units will eliminate the necessity for the making of other die units when the character of the work is to be changed, or it is desired to produce a particular job, and it will be necessary only to select appropriate dies from those already in stock, and set up the press in conformance with the requirements of the new work.

Having thus described my invention, what I claim and desire to secure by Letters Patent of the United States, is:

1. The combination of a pair of co-acting flexible dies for bending metal plates in the direction of their width, each of the dies of the pair comprising a set of interchangeable die units arranged respectively to bear against the edges of the plate to exert a bending pressure and upon the sides of the plate to exert a clamping pressure.

2. The combination of a pair of co-acting flexible dies for imparting an edgewise bend to a wide metal plate, comprising complemental die members, each of the pair composed of a set of separate die units having their acting faces formed to bear upon the edges of the plate at points staggered or alternated with relation to each other, and to bear upon the sides of the plate to prevent buckling during the bending operation.

3. A plate bending die member comprising die units in multiple, each unit of which die member is formed with an acting face for engaging one edge of the plate for a bending operation and a plane surface for engaging one side of the plate to prevent buckling of the plate during such bending operation, in combination with a die member engaging the other edge and side of the plate in such operation.

4. A plate bending die member adapted to change the contour of the edge of a thin metal plate having a width greatly in excess of its thickness, the said die member

- being composed of an assembly of interchangeable die units each of which has an edge engaging face of approximately the gage of the metal plate to be bent, and a 5 plane surface to engage the side of the plate to prevent buckling in the bending operation, in combination with a die member engaging the other edge and side of the plate in such operation.
- 10 5. In a press for imparting an edgewise bend to a thin metal plate, a complementary set of die members, such members being each composed of a plurality of die units provided with an edge engaging face and a 15 plane surface extending therefrom, with said plane surfaces of said units lying in different planes in some of the dies to permit expansion of the plate in certain areas when pressure is applied to the edges thereof.
- 15 6. In a sheet metal working press, a plurality of die units each of which has an acting face for engaging the edge of the plate and a plane surface to engage the sides thereof, the said plane surfaces lying in differ-
- ent planes in some of the die units, to preserve the gage of the plate in certain areas, and to permit expansion of the gage in other areas to produce an integral reinforcement, when pressure is applied to the edges of the plate, in combination with a die member 30 engaging the other edge and side of the plate.
7. In a sheet metal working press, complementary die members each composed of interchangeable die units provided with an acting face for engaging the edge of a metal plate and plane surfaces normally out of engagement with the sides of the plate but adapted to contact therewith in the expansion of the plate under compression applied 35 by the die units against the edges thereof.

In testimony whereof, I have signed my name at Milwaukee, this 7th day of September 1921.

R. STANLEY SMITH.
